UNITED STATES PATENT OFFICE.

CHARLES H. BARTLETT, OF CAMBRIDGE, MASSACHUSETTS.

LEDGER-HOLDER.

1,253,567.

Specification of Letters Patent. Patented Jan. 15, 1918.

Application filed October 10, 1912. Serial No. 725,037.

To all whom it may concern:

Be it known that I, CHARLES H. BARTLETT, a citizen of the United States, and resident of Cambridge, in the county of Middlesex and State of Massachusetts, have invented certain new and useful Improvements in Ledger-Holders, of which the following is a specification.

This invention relates to holders for supporting books in opened position, and the object of my present invention is to provide such a device which will hold ledgers and other similar large books for convenient reference on a table or desk, the structure being such as to allow the book to be turned or opened from side to side, and also so as to allow the framework on which the book ordinarily rests to be shifted relatively to the support in order that it may be drawn forward and returned again.

Further objects of the invention are to provide improvements in structure which will enable the book to be so inclined as to make it convenient for writing therein or to be lowered partially below the front edge of a table or desk and hold it there for convenience of reference to the contents of such book, without liability of being overbalanced and tilted off the table by the book. To these ends the invention consists in the improvements which I will now proceed to describe and claim.

Of the accompanying drawings:

Figure 1 is a side elevation of my improved holder in one of its embodiments, the parts being adjusted to a position which will permit a portion of the book to extend below the level of the top of a table or desk;

Fig. 2 is a plan view of the device, but indicating the rest or platform in substantially the position which it occupies when the book is to be horizontal or nearly so;

Fig. 3 represents a section on line 3—3 of Fig. 2, and showing a book open thereon.

Similar reference characters indicate the same or similar parts in all of the views.

A post or standard 10 is supported by a base 11, the latter being formed with a recess 12, substantially triangular in form as indicated in Fig. 2, for a purpose herein-after described. The post or standard 10 in the embodiment of the invention illustrated is a very short one. Obviously it may be longer if necessary. The base has a flat bottom surface which is substantially at right angles with the axis of the standard 10, and

extends outwardly therefrom so that the base supports the standard vertically and may be moved to locate the standard at various distances from the edge of a table 60 on which the base rests loosely.

The post or standard is preferably hollow or tubular in form, and the upper end thereof terminates in a horizontal disk 16. Below said disk the post is formed with an 65 offset 17 providing a recess 18, as best shown in Fig. 1. A pin 19 is rotatably mounted in the upper end of the post and has its lower end screw-threaded to enter a nut 20 in the recess 18, whereby said pin 19 is retained 70 in its position. The pin 19 is formed with a horizontal disk 21, between which and the disk 16 is a friction washer 22 of leather or other suitable material. Rising from the disk 21 is an ear 23, against one side of which 75 is held, by means presently described, an ear 24 extending downwardly from a bar 25. A friction washer 26 of leather or other suitable material is interposed between the ears 23, 24, a bolt 27 having a wing nut 80 28 holding the ears 23, 24 together. This structure of the two coöperating pairs of disks enables the bookrest to be swung or rotated on a vertical axis without too great freedom of movement, and also enables the 85 bookrest to be rocked on the bolt 27 so as to alter the inclination of the book downward from a horizontal position to a nearly vertical position.

When the bookrest is swung downward to 90 such a position as indicated in Fig. 1, the bar 25 enters the recess 12 of the base, enabling the book to incline downwardly below the edge of a desk or table on which the device is placed, such desk or table being indicated in Fig. 1 at b. The fact that the base 11 is cut away or recessed in the form indicated in Fig. 2 provides bearing portions 95 each side of the cut-away portion which will afford practically as much support when the 100 bookrest or platform is swung upwardly, and the base 10 pushed rearwardly on the desk or table, as though said base were not cut away at all.

The bookrest or platform which immediately supports the book comprises a center bar 29 having a removable rib 30, said rib, with the bar 29, presenting a longitudinal undercut groove which fits upon the dovetail-shaped upper edge of the bar 25 so that 110 said bar 29 and its rib 30 may be slid longitudinally of the bar 25 to bring the book

toward the user or shift it farther back, without shifting the base 11.

Other portions of the improved bookrest or platform comprises a rectangular frame 31 suitably secured to the center bar 29 and a bottom ledge 32 suitably connected to the frame 31 as by rods 33.

The side bars of the frame 31 are provided with wings 34, the lower edges of which are covered with cloth or leather, or other suitable soft material indicated at 35. Adjustable ribs 36 are provided, said ribs having their ends mounted upon the upper and lower bars of the rectangular frame 31, said ribs being adjustable toward and from each other by a right and left hand screw 37 having an end handle 38 so that the user, by either hand grasping a handle 38, may rotate the screw 37 to adjust the ribs 36 toward and from each other.

In order to hold the bar 29 in position lengthwise of the bar 25 I provide suitable means, such as a binding screw 39 passing through one side of the bar 29 and bearing against the side face of the bar 25.

To prevent the bookrest or platform from sliding off from the bar 25, suitable co-operating stops are provided, such as a stop 40 extending downwardly from the lower edge of the rib 30 and adapted to contact with a stop 41 projecting laterally from the bar 25.

When a book such as a ledger or other large book is placed upon the rest or platform, as indicated in Fig. 3, the covers *a* will rest upon the side members of the rectangular frame 31 in such position that the leaves *a* of the book can be readily turned from side to side. The adjustable ribs 36 do not clamp or pinch the back of the book, but they lie in the grooves between the heavy covers and the stiff back of the ledger so as to prevent the book from slipping sideways. The ledge 32 prevents the book from sliding down.

The device is intended chiefly where its use is but temporary and where it is desired to change one large book for another from time to time. The bookrest or platform 56 may be swung about in a horizontal plane on the axis of the pin 19, and may be swung vertically on the axis of the bolt 27. The said rest or platform may be slid forward or backward along the bar 25, this sliding movement coöperating with the means for adjusting in two planes just described, to enable the platform to stand either almost vertically, or horizontally, or at any desired intermediate position, the structure enabling 60 the book to hang with a portion of its length below the surface of a desk or table when the base 11 is drawn to the front edge thereof. Therefore a large book may be brought down almost into the user's lap, thus facilitating inspection of the contents of the book

without injury to said book. When the base 11 is pushed back on the desk or table toward the left from the position shown in Fig. 1, the book may be held in a convenient position for copying therefrom. If, when the base is pushed back on the table as last described, the bookrest or platform is shifted forward along the bar 25, the front ends of the wings 34 will operate as feet bearing upon the top of the desk or table, the soft covering 35 preventing marring the latter, thus steadyng the book platform. The same wings 34 and their edge coverings 35, by bearing against the front edge of the desk or table when the device is used in such position as indicated in Fig. 1, will steady the platform and also prevent marring the edge of the desk.

If desired, the edges of the leaves of the book may be prevented from sagging by 25 supporter mechanism such as illustrated and claimed in my application for book-holder executed of even date herewith.

When the device is to be supported on a desk or table, the base 11 should be provided with a soft pad or facing 11^a to bear on the supporting surface and prevent disfiguration thereof.

When the base 11 is a metal casting the pad 11^a may be made of sheet asbestos 95 preferably composed of interwoven asbestos threads or strips forming a refractory cloth, and attached to the base by the operation of casting the latter, the refractory pad being placed in the mold which forms the 100 base. The molten metal poured into the mold conforms to the inner surface of the pad, tongues or roots being thus formed which enter the recesses and crevices in the pad, so that when the metal hardens it is 105 firmly united to the pad. The inner surface of the pad may be roughened or indented to form cavities to be filled by said tongues or roots.

It will now be seen that the device comprises a base 11 having a flat bottom surface adapted to rest loosely on a table top, a standard 10 perpendicular to the base, and centrally arranged relatively thereto, and a book-supporting platform 31 adjustably connected with said standard and adapted to be inclined relatively thereto. Owing to the fact that the base is interrupted by a recess 12 at one side of the standard and has an uninterrupted and weighted portion at the opposite side of the standard, the base is adapted to coöperate with the table top in supporting the standard and platform in a vertical position, and relatively near the edge of the table top 125 when the base is adjusted on the table top to cause its recessed portion to overhang or project from said edge, as shown by Fig. 1. When a book *a* is deposited on the platform and the bar and platform are inclined, as 130

shown by Fig. 1, the platform wings 34 bear on the edge of the table top at points at opposite sides of the recessed portion of the base, and coöperate with said edge in steady-
5 ing the platform and book. The table top and the edge thereof coöperate respectively with the weighted portion of the base and with the platform wings in preventing the standard, platform and book from tipping
10 outwardly or to the right from the position shown by Fig. 1. A ledger or other heavy book may therefore be supported in a nearly vertical position with its lower end projecting below the table top, and its pages in
15 convenient position for inspection by a person seated at the table, the user of the book being entirely relieved of the duty of supporting the book.

Having described my invention, I claim:
20 1. A book-holder comprising a base adapted to rest loosely on a table top; a standard perpendicular to the base and affixed centrally thereto, a book-engaging platform adjustably connected with said standard and
25 adapted to be inclined relatively thereto, the base being provided with a recess at one side of the standard and having a weighted portion at the opposite side enabling the base to support the standard and
30 platform relatively near the edge of the table top when the recessed portion of the base overhangs the edge of said top, and wings depending from opposite ends of said platform and adapted to bear on the edge of the table top at points at opposite sides of the recessed portion of the base when

the platform is inclined, whereby the edge of the table top is caused to steady and partially support the platform and book, with the lower end of the book projecting
40 below the table top, the weighted portion of the base and the table top coöoperating with said wings and the table top edge in preventing the standard and platform from tipping outwardly.

2. A device of the character described comprising a base having a standard, a platform adjustably connected with said standard, and wings having edge coverings and depending from said platform.

3. A device of the character described comprising a base having a standard, a rectangular frame adjustably connected with said standard and having raised side bars to support the covers of a book, and ribs adjustably mounted upon the upper and lower bars of said frame for supporting the book adjacent the back of the book binding.

4. A device of the character described comprising a standard, a rectangular frame adjustably connected therewith, ribs mounted upon the transverse members of said frame, and a right and left hand screw for adjusting said ribs toward and from each other.

In testimony whereof I have affixed my signature, in presence of two witnesses.

CHARLES H. BARTLETT.
